UNITED STATES PATENT OFFICE.

HAROLD WHITEMAN WOODALL, OF WIMBORNE, AND ARTHUR McDougall DUCKHAM, OF UPPER PARKSTONE, ENGLAND, ASSIGNEES TO ISBELL-PORTER COMPANY, OF NEWARK, NEW JERSEY, A CORPORATION OF NEW YORK.

APPARATUS FOR DISCHARGING SUBSTANTIALLY VERTICAL RETORTS FOR THE DESTRUCTIVE DISTILLATION OF COAL.

1,065,572.

Specification of Letters Patent.

Patented June 24, 1913.

Application filed February 1, 1909. Serial No. 475,474.

To all whom it may concern:

Be it known that we, HAROLD WHITEMAN WOODALL, residing at Royston, Wimborne, and ARTHUR McDougall DUCKHAM, residing at Walden, Alexandra Road, Upper Parkstone, in the county of Dorset, England, civil engineers, subjects of the King of Great Britain, have invented certain new and useful Improvements in Apparatus for 10 Discharging Substantially Vertical Retorts for the Destructive Distillation of Coal, of which the following is a specification.

Our invention relates to apparatus for discharging substantially vertical retorts, and 15 the construction and arrangement of the retort is such that the charge of the retort is supported on an inclined surface at such an angle beneath the retort, that although it supports the greater part of the weight of 20 the charge, it does not prevent the discharge of the coke by gravitation, and in which, for regulating the free discharge of the coke, there is an extracting roller at the lower end 25 of the inclined surface, such a roller preferably having spirally arranged teeth and being rotated on its axis to govern the discharge.

Even when the extracting roller has teeth, owing to the fact that the coke is of such 30 size that the angle between one row of teeth or the blade equivalent thereto and the next row, or blade, cannot be small lest the coke be not engaged, the coke is not continuously moved or stirred.

According to the present invention, the 35 stirring of the coke is rendered continuous. This may be done for instance, by arranging the teeth so that they are equivalent to helical blades, or by substituting actual helical blades for the rows of teeth. Thus the coke leaving the retort is always in contact 40 with a blade at one or more points and prevented from slipping, and at the same time is also continuously stirred.

The object of our invention is to provide 45 a construction and arrangement of parts effecting the above stated operations which is cheap to build, easy of access, inexpensive to repair, and other evident functions and advantages of the specific constructions and 50 arrangement of the parts, which will herein-after appear from the detailed description

of the invention and the manner of applying the same.

Our invention consists in structural embodiment of the above features and in specifically effective relative arrangement of parts, all of which will be more particularly described in the following specification and then clearly pointed out in the appended claims.

Reference is had to the accompanying two sheets of drawings, forming a part of this specification, in which similar reference characters indicate corresponding parts throughout the several figures.

Figure 1 is an end elevation of our invention. Fig. 2 is a vertical section on line II—II of Fig. 3. Fig. 3 is a section on line III—III of Fig. 2. Fig. 4 represents in elevation a number of the sections composing the discharging or extracting roller, and Fig. 5 represents a modified form of the spirally arranged discharging roller.

Referring to the drawings, 1 is the retort, 75 the lower end of which is only indicated and rests in an iron ring 2, which is suitably supported above the floor of the plant by the uprights 3, and horizontal iron and concrete framework 4. While we have shown 80 only one vertical retort, it will be readily seen that our invention comprises a system of retorts which are kept full of coal by means of any suitable green coal charging device located at their top and which 85 form no part of our present invention. The coal descends through the hot retorts and is carbonized, coming out at the bottom as coke which is partially supported at the bottom on the inclined surface or sloping side 90 5 of the gas tight hopper 6. The lower end of said sloping side 5, as shown in Fig. 2, is located just to the outer side of a vertical line dropped from the bottom opening of retort and the coke discharging will be 95 made to assume such a position as to continually slip toward the extracting roller 7. This coke is prevented from sliding off the inclined surface 5 by the extracting roller 7, which is preferably built up from a series of helical blades, so that some portion of its edge is always in the proper position for spilling over some of the coke and making the operation a continuous one. For

convenience in manufacture, this extracting roller 7 consists, as shown, of fourteen separable sections 8, 8, as shown in Fig. 4, which slide on a square shaft 10. The square opening 9 in each of the sections 8, is arranged differently so that when they are slipped over the square shaft 10 in proper succession, they will have rotation through ninety degrees, as indicated in Fig. 3. While we have shown our preferred form of extracting roller, it may be readily seen that the extracting roller could be made in one piece as shown in Fig. 5.

11, 11, are swinging pendants pivotally supported on a rod 12, and are arranged so that their lower ends almost touch the extracting roller 7, and thereby prevent any loose pieces of coke from running over the top of the roller and causing an irregular or intermittent discharge of coke.

13 is a discharging drum revolving in a close fitting and circular casing 15 situated below the extracting roller, and consists of a hollow cylinder closed at both ends and having an opening 14 at part of its circumference. When the opening 14 is on the upper side, this drum 13 is free to receive the coke from the extracting roller 7, and when the opening 14 revolves to the lower side it discharges through an opening 16 in the lower side of casing 15 into any suitable conveyer or barrow for final removal. This drum 13 may be held against the casing 15 by means of the adjustable springs 17, 17, so as to make a gas tight joint between the drum 13 and inclosing casing 15.

18, 18 are holes in the inclined surfaces 5 directly under the middle of the retort, which are closed by removable plugs 19, 19, and are for the purpose of permitting the insertion of a bar to loosen up the coke when stuck in the apparatus.

20 is a sprinkler which receives water from a pipe 21 and is for the purpose of throwing water upon and quenching the coke resting upon the inclined surface 5 and extracting roller 7.

The proper rotation of the extracting roller 7 and discharging drum is accomplished by providing a rocking shaft 22, which receives its motion from any suitable source of power. At one end of said shaft 22 is provided a slotted crank arm 23 which is engaged by one end of an adjustable lever 24, while its other end engages one end of an oscillating lever 25. The other or free end of the lever 25 is provided with a pivoted sector 26, having a V-shaped edge engaging a V-shaped groove in the periphery of the wheel 27, said wheel 27 being keyed to an exterior end of the square shaft 10 which passes through a stuffing box and carries and rotates the extracting roller 7, see Fig. 3.

28 is a toothed wheel connected with the

shaft 29, which rotates the drum 13, and is engaged by a pawl 31, pivotally supported on the oscillating arm 30, said arm being operated by a link 32, connected to the crank 33, attached to the opposite end of 79 rock shaft 22, from that of slotted arm 23.

From the foregoing described structure and arrangement of parts it will be seen that the extracting roller 7 has a constant rotation and the receiving drum 13 has a 75 corresponding rotation and both are operated from a single source of power.

It will also be seen that the extracting roller 7, and drum 13, can be made to be inoperative or rotate independent of each 80 other, by the lifting or disengaging of the sector 26 or pawl 31.

From the foregoing detailed description and mode of operating the invention it will be clearly seen that we have devised a discharging device for coke ovens which can be easily and quickly adjusted or repaired, and we have perfected an apparatus in which all the objects set out in the statement of invention are fully attained and efficiently 85 carried out.

Various changes may be made in the details of our invention, and it will be obvious to those skilled in the art that the same may be modified in many ways without changing 95 the operation of the machine or departing from our invention.

Having thus fully described our invention, what we claim as new and desire to secure by Letters Patent is as follows:— 100

1. A coke discharging device comprising a substantially vertical retort having an open bottom, a downwardly inclined support directly under the open bottom, beginning at the lower end of one wall and terminating directly below the other wall of the retort, and adapted to sustain the weight of the coke in the retort, a rotary extracting or discharging roller having helical blades formed by a series of separate and independent sections secured to a shaft, said extracting roller being situated at and projecting above the lower end of the inclined support and adapted to retain and engage the coke on the said inclined support, a gas 115 tight coke receiving and discharging drum below the extracting roller, means for independently and intermittently operating said extracting roller and discharging drum.

2. A coke discharging device comprising 120 a substantially vertical retort having an open bottom, a downwardly inclined support directly under the open bottom, beginning at the lower end of one wall and terminating directly below the other wall of 125 the retort, and adapted to sustain the weight of the coke in the retort, a rotary extracting roller situated at and projecting above the lower end of the inclined support and adapted to retain and engage the coke on the said 130

inclined support and a series of movable pendants supported above and terminating above and near the periphery of the extracting roller, a gas tight coke receiving and 5 discharging drum below the extracting roller, and means for independently and intermittently operating said extracting roller and discharging drum.

3. A coke discharging device comprising 10 a substantially vertical retort having an open bottom, a gas tight chamber connected with and attached to the bottom of the retort and provided with a downwardly inclined support directly under the open bottom, beginning at the lower end of one wall 15 and terminating directly below the other wall of the retort, and adapted to sustain the weight of the coke in the retort, a sprinkler adapted to throw water on and 20 quench the coke resting on the support, a

rotary extracting roller of separate and independent sections and situated at and projecting above the lower end of the inclined support and adapted to retain and engage the coke on the said inclined support, a 25 series of movable and independent pendants supported above and terminating near the periphery of the extracting roller, and a coke receiving and discharging drum below the extracting roller, and means for independently and intermittently operating said extracting roller and discharging drum. 30

In testimony whereof we affix our signatures in the presence of two witnesses.
